UNITED STATES PATENT OFFICE

116,038

DESIGN FOR A GOGGLE

Eugene J. Lux, New York, N. Y., assignor to Columbia Protektesite Co., Inc., Carlstadt, N. J., a corporation of New Jersey

Application June 16, 1939, Serial No. 85,518

Term of patent 7 years

To all whom it may concern:

Be it known that I, Eugene J. Lux, a citizen of the United States and resident of New York city, (Borough of Manhattan), in the county and State of New York, have invented a new, original, and ornamental Design for a Goggle, of which the following is a specification, reference being had to the accompanying drawing, forming a part thereof, and of which Figure 1 is a view in front elevation of a goggle showing my new design; Figs. 2 and 3 are sectional views thereof on the lines 2—2 and 3—3 respectively, of Fig. 1; Fig. 4 is a fragmentary sectional view thereof on

the line 4—4 of Fig. 1; Fig. 5 is a rear perspective view of the same in partially open position; Fig. 6 is a view thereof in rear elevation in closed position; and Fig. 7 is a top view thereof in closed position.

The dominant feature of the design consists in the configuration of the front face of the main frame of the goggle.

I claim:

The ornamental design for a goggle, substantially as shown and described.

EUGENE J. LUX.
